UNITED STATES PATENT OFFICE.

WILLIAM H. PENNOCK, OF WILMINGTON, DELAWARE, ASSIGNOR OF ONE-HALF TO JOHN P. SPRINGER, OF SAME PLACE.

DESIGN FOR A CULTIVATOR-PLATE.

SPECIFICATION forming part of Design No. 15,591, dated December 2, 1884.

Application filed September 16, 1884. Term of patent 14 years.

To all whom it may concern:

Be it known that I, WILLIAM H. PENNOCK, a citizen of the United States, residing at Wilmington, in the county of New Castle and State 5 of Delaware, have invented certain new and useful Improvements in Designs for Cultivator-Plates; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a representation of this invention, and is a front view. Fig. 2 is a vertical section through the center.

This design has relation to cultivator-plates; and it consists in the novel form of the plate, 20 its obtuse-angle salient ends terminating in short offset edges at the sides, which are connected by long concave curved side edges, as hereinafter shown and described.

In the drawings, the letters A and B designate the salient obtuse-angle ends of the plate, 25 having the points C. At the opposite ends

of each edge are short offset edges D, which extend parallel to the middle line of the plate. These offset edges are usually straight, but may be rounded.

30 E E represent the side edges of the plate, which are curved inwardly in concave form, as shown. The plate is isometric, and these lateral concave edges extend from the offset edges D at one end of the plate to those at the 35 other end thereof, as shown. The form of the plate is thus gradually reduced from the broad angular edges to the middle portion.

What I claim, and desire to secure by Letters Patent, is—

40 The design for a cultivator-plate, having the obtuse-angle salient ends terminating in short offset edges D at the sides, and the long concave curved side edges, E E, connecting said offset edges, as shown and described. 45

In testimony whereof I affix my signature in presence of two witnesses.

WILLIAM H. PENNOCK.
